E. R. KOESTER

ADDING MACHINE

Filed June 28, 1920

Edwin R. Koester INVENTOR

N. R. Koest HIS ATTORNEY.

UNITED STATES PATENT OFFICE.

EDWIN R. KOESTER, OF ERIE, PENNSYLVANIA.

ADDING MACHINE.

Application filed June 28, 1920. Serial No. 392,392.

To all whom it may concern:

Be it known that I, EDWIN R. KOESTER, a citizen of the United States, residing at Erie, in the county of Erie and State of Pennsylvania, have invented new and useful Improvements in an Adding Machine, of which the following is a specification.

This machine is designed to form adding operations in a very simple manner.

10 The invention is illustrated in the accompanying drawings as follows:

Fig. 1 shows a plan view of the device, a part being broken away to better show construction.

15 Fig. 2 a section on the line 2—2 in Fig. 1.

1^a marks a base. This has a dial socket arranged in its upper face. 2 is a movable dial rotatively mounted in the socket 1^a, and 3 a stationary dial mounted on the 20 base 1 and overlapping the movable dial. The movable dial has a series of numbered spaces 4. These numbered spaces are in the form of elongated notches and the stationary dial 5 has a series of numbered 25 spaces corresponding to the spaces 4. The stationary dial is provided with a stop 6 at the zero position.

In using the machine the movable dial 2 is brought to the zero position, that is, 30 with zero at the stop 6. Any implement, such as a lead pencil, is placed in the slot or notch 4 opposite the number on the stationary dial which it is desired to add. The movable dial is then carried forward until 35 the pencil or implement engages the stop 6. The implement is then replaced in the notch opposite the number on the stationary dial which is the next number it is desired to add and the movable dial is again moved 40 to the stop 6. This is repeated as often as the numbers are added and the sum will be indicated opposite the space 4 at the zero position, that is to say, if it is desired to add 4, the pencil would be placed in the 45 notch opposite the space numbered 4 on the stationary dial which is the notch opposite the numeral 4 on the movable dial and this would be carried to the zero position. If 9 is then to be added the pencil would be placed in the notch opposite the space 9 50 on the stationary dial which because of the fact that the movable dial had been moved forward four spaces would be the space 13 and with the pencil in the notch opposite 55 the space 9 the movable dial is carried for-

ward to bring this notch to the zero position. 13 on the movable dial then would be at the zero position and would be the reading which would indicate the addition. This process may be repeated as often as 60 desired up to the number contained on the movable dial.

In order to yieldingly hold the movable dial in proper relation to the stationary dial and in adjusted position I prefer to 65 provide a yielding detent mechanism for yieldingly holding the movable dial in adjusted position. A series of detents 7 corresponding to the spaces on the dial are carried on the periphery of the dial. A mov- 70 able detent 8 is carried by the pin 9. The pin 9 has a head 10 which operates in a socket 11. A spring 12 is arranged in the socket against the head 10 and yieldingly crowds the detent 8 into engagement with 75 the teeth or detents 7 so as to position the spaces on the movable dial opposite the spaces on the stationary dial and yieldingly holds the movable dial in adjusted position.

It may be desirable to give the machine a 80 capacity above one hundred and this is accomplished by the following mechanism: A scroll 13 is formed on the bottom of the socket 1^a. A block 14 is slidingly mounted in the slot 15 in the movable dial. It has 85 projecting shoulders 16 which hold the block in position in the slot 15. A detent pin 17 operates in the scroll grooves 13. The detent is carried by a pin 18. The pin 18 has a head 19 against which a spring 20 90 operates to yieldingly hold the detent pin 17 in the groove 13. The block 14 has a pointer 21 which operates over spaced numbers 22, the numbers 22 being so spaced relatively to the scroll that the pointer will 95 move from one to another with each revolution of the movable dial. It will readily be seen that as the movable dial passes the hundred mark the hundreds will be indicated in the series of numbers 22. 100

It may be desirable to add more than one hundred in a single operation, as for instance, 109. If this is desired the pencil is placed in the slot 9 toward the inner end of that notch and the length of the notch is 105 such and so positioned relatively to the stop 6 that with the pencil at the inner end of the notch it will pass the stop 6 and the dial may be completely rotated and on the second turn by moving the pencil to the outer end 110

2
of the notch it is arrested by the stop 6 at the completion of the movement. Similarly any number up to the number of hundreds indicating the capacity of the machine may be added.

I prefer to provide a stop 23 which when the block 14 is moved to bring the pointer 21 to zero position will contact the stop block 14 as the movable dial is rotated in a reverse direction. The groove of the scroll 13 is so shaped that the detent 17 can be readily moved radially in the slot and across the scrolls so as to bring it into the last scroll at zero position and then with the necessary rotative movement in the backward direction the block can be brought immediately to the stop so that the device is completely re-set.

What I claim as new is:—

1. In an adding machine, the combination 20 of a rotating dial having numbered spaces with notches in the spaces; a stationary dial adjacent to the movable dial having corresponding numbered spaces; and a stop adapted to engage an implement in the 25 notches of the rotating dial at the zero position of the stationary dial, said notches being elongated to permit an implement in one end of the notch to clear the stop and in

the other end of the notch to engage the stop.

2. In an adding machine, the combination 30 of a rotating dial having numbered spaces; a stationary dial adjacent to the numbered dial having corresponding numbered spaces; a scroll opposite the rotating dial; means 35 sliding on said rotating dial and operating in the scroll indicating the number of rotations of the rotating dial, said means having a yielding engagement with said scroll permitting the movement of said means radially 40 by radial pressure to re-set the device; and a stop in the path of said means when moved to zero position whereby the rotating disc may be set at the zero position.

3. In an adding machine, the combination 45 of a base having a scroll in its face; a stationary dial on the base; a rotating dial operating in conjunction with the stationary dial; a slot in the rotating dial; a device engaging the scroll and movable in the slot indicating the number of rotations; and a stop 50 engaged by said device for re-setting the device at the zero position.

In testimony whereof I have hereunto set my hand.

EDWIN R. KOESTER.
